UNITED STATES PATENT OFFICE.

JONAS B. HOLMES, OF LOS ANGELES, CALIFORNIA, ASSIGNOR TO HOLMES-BOWMAN DRY PLACER MINING CO., A CORPORATION OF ARIZONA TERRITORY.

GOLD-SAVING MACHINE.

No. 799,161.

Specification of Letters Patent.

Patented Sept. 12, 1905.

Application filed December 6, 1904. Serial No. 235,733.

To all whom it may concern:

Be it known that I, JONAS B. HOLMES, a citizen of the United States, residing at Los Angeles, in the county of Los Angeles and State 5 of California, have invented new and useful Improvements in Gold-Saving Machines, of which the following is a specification.

My invention relates to machines for separating the free gold in gravel deposits from 10 the surrounding material without the aid of water; and the object thereof is to provide a simple and efficient machine for that purpose having a large capacity. I accomplish this object by the machine described herein and 15 illustrated in the accompanying drawings, in which—

Figure 1 is a side elevation of my gold-saving machine. Fig. 2 is a plan of the same. Fig. 3 is a front elevation, partly in section, 20 of the separating or dry-washing boxes and their operating mechanism, other portions of the machine being omitted for clearness of illustration. Fig. 4 is a longitudinal section of a portion of the feeding mechanism. Fig. 25 5 is a perspective view of a portion of a separating-box. Fig. 6 is an enlarged cross-section of two separator-boxes. Fig. 7 is a plan view of the elevator-feed-controlling mechanism.

30 In the drawings, in Fig. 1 I have shown my machine in operation for working the auriferous gravel 8, which is raised by means of the elevator 9 and deposited in the screening-chute 10 upon the coarse screen 11, which 35 serves to screen out the larger rocks which are usually found in such material. A second screen 12, finer than the screen 11, removes smaller rocks from the gravel, and the rocks which are thus screened out pass 40 through chute 13 and are delivered upon the traveling apron 14, which carries them out of the machine and deposits them upon the dump at the back of the machine. The finer material is delivered from the screening-chute 45 into a trough 15, from which it is led, by means of the flexible tubes 16, into the feed-hoppers 17 of the separating-boxes 18.

As shown in Figs. 1 and 3, my machine is 50 preferably constructed of batteries of separating-boxes, of which there are twelve on each side. The lower three of these separator-boxes are connected by spouts 19 with the feed-hopper, and the upper one is connected with the feed-hopper by a port 20 in the bot-

tom of the feed-hopper. In the bottom of the 55 separator-boxes are staggered hackle-pins 21 to cause the disintegration of any loosely-compacted gravel that is fed into the boxes. As shown in Figs. 3 and 6, the gravel is received into the separator-boxes at the central 60 portion thereof, and on each side of the point where the gravel is received into the box are swinging gates 22, which permit the gravel to work to the ends of the boxes as the same are tilted, as hereinafter explained, but prevent the gravel from going back, when the material passes out of the boxes through the gangue-spouts 23 and is delivered either upon the traveling apron 14 or upon the deflecting-apron 24, on which it slides to the traveling apron, which carries it out of the machine to the dump. The gold-dust, however, is prevented from entering the gangue-spouts by the ore-troughs 25, which are preferably set on edge, as best shown in Figs. 5 and 6. Below each swinging gate, except those nearest the point where the gravel is delivered into the box, are retarding-ribs 26, which form a species of riffle, as best shown in Figs. 5 and 6. These banks of separator-boxes are pivotally connected to the supporting-standard 27, there being one of these standards at each side of each battery of boxes. These standards rest loosely in sockets 28 in the bottom timber 29. Those in the center of the 85 machine are guided by yokes 30. Those on the outer sides of the machine are connected to a bifurcated bar 31, the furcations of which pass around a vertical timber of the frame. The other end of this bifurcated bar 90 is pivotally connected to one arm of bell-crank lever 32. The other arm of this bell-crank lever is connected to pitman-rod 33, which is secured to the crank-pin 34 of the crank 35, secured upon shaft 36, which crank 95 upon the rotation thereof through its connecting mechanism causes an oscillating movement of the separator-boxes. These separator-boxes are connected by a bar 37 to crank 38, rigidly secured to shaft 39, which 100 shaft carries a mutilated gear 40, the teeth of which cover only one-half the circumference of the wheel and mesh with a rack-bar 41. Gear 40 is loosely mounted on shaft 39, connected to crank 42, secured upon shaft 43, 105 which shaft carries sprocket-wheel 44, which is driven by sprocket-chain 45, which chain passes over sprocket-wheel 46 on shaft 47.

This shaft carries a sprocket-wheel 48, over which passes sprocket-chain 49, which passes over a sprocket-wheel 50, which last sprocket-wheel is mounted upon shaft 36, to which is rigidly affixed driving-pulley 51, to which power is applied to operate the machine. The elevator is composed of buckets 52, which are secured at each end to chains 53 and 54, which chains pass over sprocket-wheels 55 and 56, secured upon shaft 47. Idler sprocket-wheels 57 change the direction of the inner side of the elevator, so as to permit the delivery of the material being elevated upon the deflecting-board 57', which deflects it into the screening-chute. The lower end of the elevator passes around a drum 58, which is mounted in the vertical swinging arms 59 and 60. The shaft 61 of this drum projects beyond the arms in which it is mounted, and on the projecting ends of said shaft are bars 62 and 63, whose inner ends are secured to a cross-bar 64. To the center of this cross-bar is secured a rope 65, which winds around a drum 66, mounted on shaft 67, which shaft is revolutely mounted in the vertical timbers of the frame of the machine. At one side drum 66 is provided with holes 68 for the reception of the operating-bar 69, by means of which the drum is rotated to feed the elevator into the material, as shown in Fig. 1, so that a considerable quantity of the same may be moved without changing the position of the machine.

In the operation of my machine, the same being in the position shown in Fig. 1, power is applied to drive-pulley 51, which through connecting mechanism operates all the other moving parts of the machine. The gravel is carried up and delivered into the screening-chute, from whence it passes through the flexible tube into the feed-hoppers and thence into the separating-boxes. As before explained, the rotation of shaft 36 through the connecting mechanism causes the oscillating movement of the separator-boxes. The rotation of shaft 43 by means of crank 42 causes the reciprocation of the rack 41, which causes the mutilated gear 40 to turn backward and forward upon shaft 39. This gear carries a dog 70, which engages a two-toothed ratchet-wheel 71, which is rigidly affixed upon shaft 39, whereby upon the movement of the rack-bar toward the elevator shaft 39 is caused to make a half-revolution, which through connection mechanism causes the tilting of the separator-boxes and upon the return movement of the rack-bar permits them to remain at the angle to which they were turned by the forward movement of the rack-bar, from which it will be seen that first one end of the boxes is elevated and the other end is depressed and that upon the next forward movement of the rack-bar the elevated end is depressed and the depressed end is raised and that during all of the time the boxes are subjected to the

reciprocatory movement, thereby causing the gold contained in the gravel to separate from the gangue and to settle to the bottom, where it is caught and held by the riffles and ore-troughs, from which it is removed as soon as a sufficient quantity thereof is collected there-in to require its removal in order to save it all. This is done by disconnecting bar 37 and then turning the boxes upside down and then turning them to cause the gold to pass out of the gangue-spouts.

To cause both batteries of separator-boxes to be tilted together, I have secured to the battery that is not connected with bar 37 at one edge thereof a bar 72, which carries an L-shaped arm 73, which arm passes over a wheel 74, secured in bearings 75, affixed to the battery of boxes which is connected to bar 37. Bar 72 passes under this wheel, so that the batteries of boxes may reciprocate independently of each other, but both sets of batteries will be tilted together. The bottoms of the separator-boxes are preferably covered with coarse gravel held thereon by glue. The traveling apron is driven by chain 76, which passes over wheels 77 and 78.

It will thus be seen that I have provided a simple and efficient machine of large capacity for recovering placer-gold by the dry-washing process.

Having described my invention, what I claim as new, and desire to secure by Letters Patent, is—

1. In a placer-gold separator; a separator-box pivotally supported in bearings; means to give said box a lateral reciprocatory movement, and means to cause the alternate elevation and depression of the ends of said separator-box, each end being alternately higher than the other end.

2. In a placer-gold separator; a separator-box pivotally supported in bearings; means to give said box a lateral reciprocatory movement; staggered hackle-pins in the bottom of said box; and means to cause the alternate elevation and depression of the ends of said separator-box.

3. In a placer-gold separator; a separator-box pivotally supported in bearings; staggered hackle-pins projecting upwardly from the floor of said box; riffles extending transversely said box; inclined gates pivotally mounted in said box, said gates permitting the flow of material toward the outer ends thereof, and preventing its flow toward the center; and means to cause the alternate elevation and depression of the ends of said separator-box.

4. In a placer-gold separator; a separator-box pivotally supported in bearings; staggered hackle-pins in the bottom of said box; riffles extending transversely said box; and means to give said box a lateral reciprocatory movement.

5. In a placer-gold separator; a separator-

box pivotally supported in bearings; staggered hackle-pins in the bottom of said box; riffles extending transversely said box; and means to cause the alternate elevation and depression of the ends of said box.

6. In a placer-gold separator; a frame; an elevator in said frame; a screening-hopper into which said elevator empties at the upper end of the frame; screens in said hopper; a trough below said screens near the lower end of said hopper; separating-boxes below said trough; feed-hoppers opening into said boxes; flexible tubes leading from said trough to said feed-hopper; hackle-pins projecting upwardly from the bottom of said boxes; said hackle-pins being staggered; riffles extending trans-

versely said boxes; inclined swinging gates above said riffles; gangue-spouts at the ends of said boxes; a traveling apron below said boxes adapted to receive the gangue and carry the same out of the machine; means to cause said boxes to reciprocate; and means to cause the ends of said boxes to be alternately raised and depressed.

In witness that I claim the foregoing I have hereunto subscribed my name this 30th day of November, 1904.

JONAS B. HOLMES.
